BREAD SLICING MACHINE

Harry J. Criner, Davenport, Iowa, assignor of
one-half to A. G. Bush, Davenport, Iowa

Application May 20, 1939, Serial No. 274,751

18 Claims. (Cl. 146—88)

My invention relates to bread slicing machines of the band-blade type, having either a plurality of endless band-blades or a continuous band-blade reeved over spaced pulleys to form a plurality of loops and cutting courses.

The objects of my invention are to provide improved means for carrying and directing the band-blades; for twisting and guiding the cutting courses of the blades; for directing and simultaneously adjusting the relative spacing of the cutting courses of the blades; for adjusting the spacing of the upper and lower guide assemblies relative to themselves and to the blade carrying drums; and improved adjusting and spacing means for the cutting courses of the blades.

I attain these objects by the means illustrated in the accompanying drawings, in which,—

Figure 1 is a side elevation of my machine looking at it from the right of Figure 2;

Figure 2 is an end view of my machine;

Figures 3, 4 and 5 are diagrammatic views showing alternative forms for the arrangement of the carrying and guiding drums, in section on the middle line of the drums;

Figure 6 is an enlarged detail plan view of the lower guide assembly and Figure 7 is an enlarged detail end view of such guide assembly, showing parts broken away;

Figure 8 is a detail diagrammatic or plan view showing the diverse angles of the upper and lower carrying drums when laterally inclined in opposite directions, and with the variation in diameter of the drums exaggerated for clearness of illustration.

Similar numerals refer to similar parts throughout the several views.

The frame of my machine comprises a base 9 to which is united a vertical column preferably T-shaped in section, having a web 1 and flanges 2 integrally united. Hubs or bosses 3, 4, 5 and 6 are formed integral with the frame and carry shafts 14, 16, 18 and 20 secured therein and which may be either revolvable or fixed as desired, and one of which may be revolvable and carry a belt-wheel 19a on the outer end thereof adjacent the frame to drive such shaft.

Upon the shafts are mounted drums 13, 15, 17 and 19 which, in the case of fixed shafts, may be revolvably mounted thereon and in the case of revolvable shafts, may be keyed to the shafts so as to revolve therewith. These drums are arranged in inner and outer pairs. A plurality of band-blades 21—22 are mounted upon the outer pair of drums and are driven thereby. The inner or deflecting drums 15 and 17 are spaced apart

and are parallel to the outer drums 13 and 19 respectively adjacent thereto and may be mounted in line vertically with their respective adjacent outer drums as shown in Figures 1 and 4 or offset slightly as shown in Figure 3 and 5.

The inner drums may comprise a single pair of inner drums as in Figures 1, 2, 3 and 4, or two upper inner drums 15—15' and two lower inner drums 17—17' may be utilized as shown in Figure 5.

The upper drums are mounted at an acute angle to the transverse axis of the machine as clearly shown in Figure 8, and the lower drums are mounted at an acute angle to the transverse axis of the machine, but are preferably inclined laterally in a direction opposite to the lateral inclination of the upper drums.

The outer drums 13 and 19 are so mounted that their middle points lie in a line parallel to the vertical side frame. In order to allow for the variation in the distance between the middle of the drums and between the outer ends of the drums due to their different lateral inclinations, the outer ends of the drums are constructed with a slightly smaller diameter than the middle points of the drums and the variation in diameter progresses regularly from the middle to the ends of the drums.

The intermediate or deflecting drums may be constructed with a corresponding variation in diameter or they may be constructed of uniform diameter from end to end as desired.

With either construction indicated, it is obvious that the angle of lateral inclination of the inner drums will cause the portions of the series of blades passing to or from the upper inner drum to travel in a plane standing at an acute angle to a similar plane on the transverse axis of the machine and will likewise cause the portions of the series of blades passing to or from the lower drum to travel in an oppositely laterally-inclined plane. The effect of this inclination is to reduce the amount of twisting of the blades required to cause the cutting courses thereof to travel in planes at right angles to the transverse axes of the machine and this reduction of angle is accomplished whether the cutting courses of the blades are crossed as in Figures 1 and 4, or the cutting courses travel in parallel planes as in Figures 3 and 5.

In order to complete the twisting of the blades necessary to turn the cutting courses thereof into planes parallel with the longitudinal axis and at right angles to the transverse axis of the machine, I utilize spaced series of fingers 12 and 55

12' which may be mounted in fixed positions upon crossbars 10 and 11, which crossbars have their ends mounted in hubs 10' and 11'. These hubs are formed integral with brackets 26 and 26' respectively and these brackets are adjustably mounted upon the flange 2.

In order to make them vertically adjustable, a longitudinal slot 23 is cut in the flange 2 and bolts 24, 24', 25 and 25' are mounted in suitable bores formed in the brackets 26 and 26' respectively and extend through the slot 23, being rigidly secured to the flange 2 by the nuts in common use, or other suitable means. When so mounted, the crossbars 10 and 11 may be moved up or down the desired distance within the limits of the slot 23 which may be made long enough to accommodate all sizes of bread.

When so constructed, the fingers 12 and 12' will act respectively as guides and supports for the bread while traveling through the cutting courses of the blades.

In order to provide for varying the lateral spacing of the cutting courses of the blades so as to cut slices of different thicknesses, instead of utilizing the fixed fingers 12 and 12' shown in Figure 2, I prefer to utilize movable fingers 12'' as shown in Figures 6 and 7. Each finger is provided with a slot through which the cutting course of a blade 21-22 may travel. These slots are preferably made wide enough to permit free travel of the blade therein, but narrow enough to prevent the blade getting out of line.

These fingers are preferably united to guide-blocks of any desired form which may be slidably mounted upon any suitable support but I prefer to use annular guide-blocks 36 upon a shaft or crossbar 29. The shaft 29 has one end secured in a hub 8 which may be formed integral with the side frame or may be mounted upon the bracket 26 or 26' as shown in Figure 2.

The crossbar 29 is provided with a longitudinal groove 38 adapted to receive the inner ends of pins 37 threaded or pressfitted in the guide-blocks 36 to prevent revolution of the guide blocks upon the crossbar 29.

The crossbar 29 may be prevented from turning in the hub 8 by a pin 30' or other suitable means. The guide-blocks 36 are provided with grooves 36' on one side thereof opposite the fingers 12''.

The hub 8 may be provided with an arm 34 the outer end of which carries a hub 35 and an enlarged annular block 30 may be mounted upon the crossbar 29 on the inside of the flange 2 and having an arm 32 carrying a hub 33. In the hubs 35 and 33 an additional shaft or crossbar 28 is revolvably mounted the outer end of which is provided with a hand-wheel 36a secured thereto by a pin 39' by which the shaft 28 may be revolved in the hubs 35 and 33.

A plurality of guide members having hubs 39 are mounted upon the shaft 28 and may be rigidly secured thereto by pins 28'. Each guide member comprises a wheel with a hub 39 and a thin disc 27' united thereto which may carry a rim 27 preferably circular in cross-section. The discs and rims of the guide members are mounted at regularly progressive angles relative to the crossbar 28, the innermost member preferably having its rim 27 standing in a plane at right angles to the crossbar, the succeeding members having their rims standing at such angles to the shaft 28 that when in their closest position of adjustment, the innermost portions of said rims will be spaced from each other on centers a distance

equal to the minimum thickness of the slices of bread to be produced by the machine and that when turned in the opposite position of adjustment, that is, when rotated one-half way around, the innermost portions of said rims will be spaced from each other on centers a distance equal to the maximum thickness of the slices of bread to be sliced, but it is obvious that the lateral slope of the rim may progress all the way around the rim, if desired, instead of half way as shown by 10 me.

In Figure 6 the innermost guide-block 36 is omitted for clearness and a portion of the rim and disc of the second guide member is omitted to more clearly show the slot 36' in the second guide-block 36. In Figure 6 the guide members are shown in the position of adjustment in which they would stand when the fingers 12'' are spaced to guide the blades to cut slices of the maximum thickness permissible.

It is obvious that as the shaft 28 is revolved and carries with it the rims 27 of the guide members, these rims being inserted in the slots of the guide-blocks 36, will necessarily cause the guide-blocks and the fingers carried thereby to travel laterally to correspond with the angular position of the rims, and the spacing of the fingers may thereby be widened or narrowed simultaneously and uniformly. It is likewise quite apparent that when the fingers move the blades laterally to change the spacing thereof, the blades will correspondingly shift laterally upon the carrying drums if, as intended by me, the change of adjustment is made while the drums are revolving.

When the hub 8 is mounted upon the bracket 26', the arm 34 will be united to the hub 8 in the same manner shown in Figure 6.

The slots 36' will be formed of sufficient depth and of such configuration as to permit the necessary maximum travel of the guide-blocks 36 upon their support 29 and the relative proportions of the slots 36' and the rims 27 may be varied as necessary to meet the requirements of any particular case.

In the operation of my machine the blades 21-22 are mounted upon the carrying drums 13 and 19 and in contact with the guiding drums 15 and 17 and the blades may be either crossed as in Figure 4 or uncrossed as in Figures 3 and 5.

In this connection let it be noted that for convenience I shall refer to the portions of the blade traveling downwardly from the middle of one side of the upper outer drum to the middle of one side of the lower outer drum as the downward reaches and to the portion of the blade traveling upwardly from the middle of one side of the lower outer drum to the middle of one side of the upper outer drum as the upward reaches. The terms "downward reaches" and "upward reaches" may also be used to apply to the portions of the blades traveling between the middle of the sides of the upper intermediate drum and the middle of the lower intermediate drum, when convenient. I shall also refer to the portion of the blades between and adjacent to the blade guide-assemblies as the cutting courses of the blades.

When the blades are mounted upon the outer drums as indicated, it is obvious that the downward reaches of the blades will travel in lines spaced laterally from the upward reaches of the blades by reason of the upper drums and the lower drums being mounted at angles to the transverse axis of the machine; and that very

little guiding action will be required by the guide fingers because the diameter of the drums and the angle at which they are mounted will be so proportioned that the upward and downward reaches will be carried approximately at the desired distance from each other laterally. However, guides will be necessary to twist the cutting courses of the blades enough farther to make the cutting courses stand at right angles to the transverse axis of the machine. The guide-assemblies are then secured in place at the desired height and distance from each other and from the inner drums.

As the drum 19 is revolved the traction of the blades upon the other drums will cause them to revolve at the same rate and as the blades pass from the inner drums to the guide-assemblies, the relative lateral inclination of the upper and lower drums will place the blades at an acute angle to the transverse axis of the machine and thus reduce the amount of twisting action which it is necessary for the guides to exercise upon the blades.

By this arrangement, I not only reduce the wear upon the blades caused by the pressure of the guides, but also the crystallization of the blades which arises from twisting of the blades and which is proportionate to the extent of such twisting. By thus reducing the wear due to contact with the guides and pressure of the guides, and by reducing the crystallization due to such pressure and to twisting of the blades the length of life of the blades will be substantially prolonged and by causing the upward and downward reaches of the blades to travel in approximately a common plane, uniform slicing action upon the bread is promoted and the difficulties which might be encountered from irregularities in the contours of the loaves are reduced or eliminated.

The action of the laterally inclined drums in separating the upward and downward reaches of the blades laterally can be accomplished by having both the upper and lower drums inclined laterally either in the same or in opposite directions relative to the transverse axis of the machine, but in cases where the blades are run uncrossed as shown in Figures 3 and 5, it is preferable to have all of the drums laterally inclined in the same direction and in such cases the amount of twisting required to turn the cutting courses into planes at right angles to the transverse axis of the machine may be reduced by the number of degrees of angle at which the drums are inclined relative to the transverse axis.

When it is desired to change the spacing of the cutting courses of the blades, the hand-wheel 36a is revolved, carrying with it the shaft 28 and the discs 27 and rims 21. The rims acting upon the guide-blocks 36 will move them laterally upon their support whether supported by the crossbar 29 or otherwise, and the movement of all the guide-blocks 36 will be simultaneous and the spacing between them will at all times be uniform.

When turned to the desired extent, they may be locked in position by a set screw 35a or any other suitable means.

As the fingers 12 move laterally, they carry with them the blades 21-22 and as the adjustment is made while the machine is running, the movement of the cutting courses of the blades will cause the blades to travel laterally along the drums a distance corresponding to the movement of their respective guide fingers.

Any of the tensioning devices in common use

may be utilized to loosen the blades so as to facilitate their movement along the drums.

It is obvious that with this arrangement of guide-assemblies, a portion, such as one-half, of the guide members may have their disc wheels and rims mounted at lesser angles than the other half so that half of a loaf of bread might be sliced with narrower slices than the other half, if desired.

It is likewise obvious that various forms of spacing apparatus may be utilized in connection with the angling drums.

Any desired form of bread chute or feed tables to carry the bread to or from the machine may be utilized with my invention and it may be utilized and synchronized with a wrapping machine of any of the forms in common use.

This application covers a machine of the general class described in my co-pending application Serial No. 240,237 now matured into Patent No. 2,160,957.

It is obvious that various modifications of my apparatus may be made without departing from the spirit of my invention and I do not limit my claims to the precise form shown or described.

I claim:

1. A bread slicing machine comprising a base with a supporting frame united thereto, upper and lower blade-carrying drums revolvably mounted in the frame spaced apart and extending transversely of the machine in parallel planes but having their axes inclined laterally in opposite directions at an acute angle to the transverse axis of the machine, intermediate upper and lower blade-deflecting drums revolvably mounted in the frame parallel to the outer upper and lower drums respectively and similarly inclined laterally, and a plurality of endless band-blades mounted upon the carrying drums and contacting the guiding drums intermediate the outer drums.

2. A bread slicing machine comprising a base with a supporting frame united thereto, upper and lower blade-carrying drums revolvably mounted in the frame spaced apart and extending transversely of the machine in parallel planes but having their axes inclined laterally at an acute angle to the transverse axis of the machine, intermediate upper and lower blade-deflecting drums revolvably mounted in the frame parallel to the outer upper and lower drums respectively and similarly inclined laterally, and a plurality of endless band-blades mounted upon the carrying drums and contacting the guiding drums intermediate the outer drums.

3. A bread slicing machine as described in claim 1, said drums being mounted at an angle of approximately five degrees to the transverse axis of the machine.

4. A slicing machine as described in claim 1, in combination with means intermediate the deflecting drums, to twist the blades in their cutting courses into uniformly spaced parallel relation.

5. A slicing machine as described in claim 1, in combination with means intermediate the deflecting drums, to twist and guide the blades in their cutting courses into uniformly spaced parallel relation and in planes extending at right angles to the transverse axis of the machine.

6. A structure as defined in claim 1, all of said drums being slightly larger at the middle than at the ends and tapered slightly from the middle to the ends.

7. A structure as defined in claim 1, said intermediate drums being slightly larger at the

middle than at the ends and regularly tapered from the middle toward both ends.

8. A structure as defined in claim 1, in combination with means intermediate the deflecting drums to twist and guide the blades in their cutting courses into uniformly spaced parallel relation and in planes extending at right angles to the transverse axis of the machine, and means for simultaneously uniformly changing the gauge 10 of such twisting and guiding means.
9. A structure as defined in claim 1 in combination with means intermediate the deflecting drums to twist and guide the blades in their cutting courses into uniformly spaced parallel relation and in planes extending at right angles to the transverse axis of the machine and with the cutting edges of all the blades throughout their cutting courses running approximately in a single transverse plane, and means for simultaneously uniformly changing the gauge of such 20 twisting and guiding means.

10. A spacing mechanism comprising a frame, a crossbar mounted thereon, a series of guide-blocks slidably mounted upon said crossbar, each 25 of said guide-blocks carrying a projecting slotted finger to receive, guide and twist a moving blade, a shaft revolvably mounted in the frame spaced from and parallel to the crossbar, a series of guide members corresponding in number to the 30 guide-blocks rigidly mounted upon the shaft, each of said guide members including a wheel, the rim of the first of said wheels standing at a right angle to the shaft and the succeeding wheel rims standing at progressively decreasing 35 angles to the shaft, slots formed in the guide-blocks to receive and co-act with the rims of the wheels whereby when the shaft is revolved, the wheel rims will slide the guide-blocks along upon the crossbar and uniformly increase or decrease 40 the spacing thereof.

11. A spacing mechanism comprising a frame, a support mounted thereon, a series of guide-blocks slidably mounted upon said support, each 45 of said guide-blocks carrying a projecting slotted finger to receive and guide a blade or other thing to be spaced, a shaft revolvably mounted in the frame spaced from and parallel to the support, a series of guide members corresponding in number to the guide-blocks mounted upon the shaft, 50 each of said guide members comprising a hub having united thereto a circular flange, the flanges of the succeeding guide members being arranged at progressively decreasing angles to the shaft, slots formed in the guide-blocks to receive and 55 co-act with the flanges of the guide members whereby when the shaft is revolved, the flanges will slide the guide-blocks along upon the crossbar and uniformly increase or decrease the spacing thereof.

- 60 12. The combination with a bread sliding machine as described in claim 1, of a crossbar mounted on the frame spaced from the cutting courses of the blades, a series of guide-blocks 65 slidably mounted upon said crossbar, each of said guide-blocks carrying a projecting slotted finger to receive, guide and twist a moving blade, a shaft revolvably mounted in the frame spaced from and parallel to the crossbar, a series of 70 guide members corresponding in number to the guide-blocks rigidly mounted upon the shaft, each of said guide members including a wheel, the rim of the first of said wheels standing at a right angle to the shaft and the succeeding wheel rims standing at progressively decreasing 75 angles to the shaft, slots formed in the guide-

blocks to receive and co-act with the rims of the wheels whereby when the shaft is revolved, the wheel rims will slide the guide-blocks along upon the crossbar and uniformly increase or decrease the spacing thereof.

13. A bread slicing machine as described in claim 1 in combination with a spaced pair of guide assemblies supported by the frame intermediate the deflecting drums, each assembly comprising a support mounted on the frame, a series of guide-blocks slidably mounted upon said support, each of said guide-blocks carrying a projecting slotted finger to receive and guide a blade, a shaft revolvably mounted in the frame spaced from and parallel to the support, a series 10 of guide members corresponding in number to the guide blocks mounted upon the shaft, each of said guide members comprising a hub having united thereto a circular flange, the flanges of the succeeding guide members being arranged at progressively decreasing angles to the shaft, slots 15 formed in the guide-blocks to receive and co-act with the flanges of the guide members whereby when the shaft is revolved, the flanges will slide the guide-blocks along upon the crossbar and 20 uniformly increase or decrease the spacing thereof.

14. In a spacing mechanism the combination with a frame of transverse supporting means mounted thereon, a series of guide-blocks slidably mounted upon said supporting means, each of said guide-blocks carrying a projecting slotted finger to receive and guide a moving blade, a shaft revolvably mounted in the frame spaced from and parallel to the supporting means, a series 30 of guide members corresponding in number to the guide-blocks rigidly mounted upon the shaft, each of said guide members including a wheel, the rim of the first of said wheels standing at a right angle to the shaft and the succeeding wheel rims standing at progressively decreasing 35 angles to the shaft, slots formed in the guide-blocks to receive and co-act with the rims of the wheels whereby when the shaft is revolved, the wheel rims will slide the guide-blocks along upon 40 the crossbar and uniformly increase or decrease the spacing thereof.

15. A bread slicing machine as described in claim 1 in combination with a spaced pair of guide assemblies supported by the frame intermediate the deflecting drums, each assembly comprising a support mounted on the frame, a series of guide-blocks slidably mounted upon said support, each of said guide-blocks carrying a projecting slotted finger to receive and guide a blade, a shaft revolvably mounted in the frame spaced from and parallel to the support, a series of guide members corresponding in number to the guide-blocks mounted upon the shaft, each of said guide members comprising a hub having united thereto a circular flange, the flanges of the succeeding guide members being arranged at progressively decreasing angles to the shaft, slots formed in the guide-blocks to receive and co-act 50 with the flanges of the guide members whereby when the shaft is revolved, the flanges will slide the guide-blocks along upon the crossbar and uniformly increase or decrease the spacing thereof, and means for adjusting the spacing of the 55 guide assemblies from the deflecting drums and from each other.

16. A bread slicing machine as described in claim 1 in combination with spaced adjustable means intermediate the deflecting drums to twist, 60

guide and space uniformly the blades in their cutting courses, whereby the blades when running may be caused to travel laterally upon the carrying drums to correspond to the lateral movement of their cutting courses.

17. A bread slicing machine as described in claim 1 in combination with spaced adjustable means intermediate the deflecting drums to twist guide and space uniformly the blades in their cutting courses, whereby the blades when running may be caused to travel laterally upon the carrying drums to correspond to the lateral movement of their cutting courses, and means to ad-

just the spacing of the spaced means relative to each other and to the deflecting drums.

18. A slicing machine as described in claim 1, in combination with uniformly adjustable spacing means arranged in two spaced series to space the cutting courses of the slicing means intermediate the drums, said spacing means, while being adjustable to change the spacing thereof, also acting to automatically change the spacing of the slicing means upon the pulleys to correspond to the changed spacing of the spacing means.
